[57] **CLAIM**

The ornamental design of a pocket microscope, as shown and described.

DESCRIPTION

FIG. 1 is a front elevational view of a pocket microscope showing my new design;

FIG. 2 is a rear elevational view thereof;

FIG. 3 is a front perspective view thereof;

FIG. 4 is a top plan view thereof;

FIG. 5 is a bottom plan view thereof;

FIG. 6 is a side elevational view thereof, the opposite side being a mirror image of the side shown;

FIG. 7 is a front elevational view of second embodiment of a pocket microscope showing my new design;

FIG. 8 is a rear elevational view of the embodiment shown in FIG. 7;

FIG. 9 is a front perspective view of the embodiment shown in FIG. 7;

FIG. 10 is a top plan view of the embodiment shown in FIG. 7;

FIG. 11 is a bottom plan view of the embodiment shown in FIG. 7;

FIG. 12 is a side elevational view of the embodiment shown in FIG. 7, the opposite side being a mirror image of the side shown;

FIG. 13 is a front elevational view of third embodiment of a pocket microscope showing my new design;

FIG. 14 is a rear elevational view of the embodiment shown in FIG. 13;

FIG. 15 is a front perspective view of the embodiment shown in FIG. 13;

FIG. 16 is a side elevational view of the embodiment shown in FIG. 13, the opposite side being a mirror image of the side shown;

FIG. 17 is a top plan view of the embodiment shown in FIG. 13; and,

FIG. 18 is a bottom plan view of the embodiment shown in FIG. 13.
